UNITED STATES PATENT OFFICE.

RALPH C. BROWNE, OF SALEM, MASSACHUSETTS, ASSIGNOR TO BROWNE APPARATUS COMPANY, OF SALEM, MASSACHUSETTS, A CORPORATION OF MASSACHUSETTS.

SPARKING PLUG.

No. 920,257.

Specification of Letters Patent.

Patented May 4, 1909.

Application filed April 25, 1903. Serial No. 154,288.

To all whom it may concern:

Be it known that I, RALPH C. BROWNE, of Salem, in the county of Essex and State of Massachusetts, have invented certain new and useful Improvements in Sparking Plugs, of which the following is a specification.

This invention has relation to sparking or igniting mechanism for combustion engines.

With the sparking plugs as hitherto constructed, it has been customary to provide several of them in order to replace the one in use, in case it fails to work properly from one cause or another, such as being covered with soot; and, again, it has been impossible to determine the character of the spark from the coil without unscrewing the plug from the cylinder or disconnecting the wires. Again, in the plugs which have been commercially used, much trouble has resulted from the close proximity of the terminals within the engine, as short circuits are frequently formed by reason of sooty deposits.

The object of the present invention is to provide a reversible plug having duplex 25 sparking terminals, so that in case one pair of terminals gets out of order, the plug may be reversed and a fresh pair located properly within the engine cylinder.

Another object of the invention is to provide a plug having two sparking terminals, one arranged within the cylinder, and the other outside of the cylinder, so that the operator may easily ascertain whether the coil is working properly in the formation of a spark.

Still another object of the invention is to provide certain improvements in plugs of the character referred to, for simplifying them, rendering them less liable to get out of order, 40 and reducing the cost of their manufacture.

On the accompanying drawings,—Figure 1 represents in side elevation a sparking plug. Fig. 2 represents the same partially in section. Fig. 3 represents a section through the core. Fig. 4 represents an end elevation of the core. Figs. 5 and 6 represent portions of the casing. Fig. 7 illustrates more or less conventionally the end of a cylinder of an engine with the sparking plug thereto attached. Fig. 8 represents another embodiment of the invention, the plug in this case being shown in longitudinal section. Fig. 9 represents a side elevation of the same. Fig. 10 represents an end view thereof. Fig. 11 55 illustrates another embodiment in side eleva-

tion. Fig. 12 represents a further embodiment in longitudinal section.

On the drawings,—*a* indicates a core which is substantially cylindrical, as shown, and which is provided midway between its ends with two oppositely extending bosses *a'* *a'* 60 These bosses project outwardly from an enlarged portion *a''* of the core. Passing through each one of the bosses, there is an electrode which is bent at an angle of 90 degrees, and passed through the end of the core. These electrodes are indicated at *b* *b'*.

The core is formed of glass, porcelain, or other suitable insulating substance or material, and by the construction shown in Fig. 70 3, it is apparent that the two electrodes *b* *b'* are insulated from each other by being embedded in the body of the core.

Each electrode has its terminal extending from the end of the core, and at the center thereof, and may be curved laterally, as indicated, and tipped with platinum.

The casing is formed of four parts, and it includes two end portions *c* *c*, and the middle portion or coupling *d*. This coupling *d*, as shown in Fig. 5, is formed in two parts so as to fit snugly around the enlarged portion *a''* of the core, being provided with apertures *d'* *d'* for the bosses *a'* of the core. It is provided at its ends with external screw-threads 80 85 *d''*, so that the end portions *c* *c* of the casing which are internally threaded may be screwed thereon.

Each of the end portions *c* *c* is provided with an electrode or terminal *c'* or *c''*, as the case may be, in close proximity to the terminal of the electrode *b* or *b'*, so as to form a spark-gap.

The casing is externally threaded at each end so that either end thereof may be screwed into the end of a cylinder, so that the electrodes will project thereinto. The electrodes or conductors *b* *b'* project beyond the bosses *a'* *a'* and may be threaded to constitute binding-posts, so that the terminal wires *s* *s'* of the secondary circuit may be secured thereto between the washers *e* *e'*, by a nut *e''*.

It is apparent from this construction that when the plug is secured in place in a cylinder, there are two spark-gaps, one within the cylinder, and the other external thereto and visible to the eye. The supplemental spark-gap or air-space in the secondary circuit outside of the combustion chamber is visible to the operator, so that he is enabled to deter- 105 110

mine the condition of the coil, battery, etc. By reason of the provision of the second or supplemental spark-gap, there is formed between the electrodes in the cylinder an efficient spark across the gap x , even though the terminals are in a foul condition, from dirt or soot.

The supplemental or visible spark causes a fixed resistance in the circuit which results in retarding the flow of the current until its voltage reaches its maximum point, and consequently the discharge in the cylinder takes place with an accumulated violence.

The operator may, whenever desired, reverse the plug so as to insert in the cylinder a fresh pair of terminals in a clean and operative condition. So far as I am aware, I am the first to have provided a plug adapted to be attached to a gas-engine having two spark gaps, and which is adapted to be reversed, and also to have provided sparking mechanism in which there are two spark gaps in stationary relation to each other, one within and one without the cylinder for the purpose of accomplishing the results to which reference has been hereinbefore made.

It is apparent that the invention may be embodied in a variety of devices. For instance, in Fig. 8, the core g is substantially the same as shown in Fig. 3, except that its ends are tapering. The casing is made in two similar halves h h' , adapted to cover the core, as shown in Fig. 9. These two parts of the casing are secured together by nuts h^2 h^2' , screwed on the threaded portions h^3 of the casing. Each end of the casing is externally threaded so that it may be screwed into the engine to bring the electrodes or terminals into the combustion chamber. In this embodiment of the invention the ends of the electrodes b b' are straight and not curved as shown in Fig. 3, whereas electrodes on the ends of the casing are bent over into proper relation thereto to leave a space or a spark-gap of the proper length.

In Fig. 11 the casing is formed in two parts, being divided by a plane at right angles to the longitudinal lines of said casing. In this case, the two halves i i' of the casing are secured together by nuts j which are screwed on threaded annuli i^3 which surround the bosses or lateral projections of the core. In this case, it is further observed that the casing is provided with a supplemental binding screw i^3 so that either pair of terminals may be placed in the igniting circuit, so as to be used independently or so that the two pairs of electrodes may be arranged in the circuit in multiple with relation to each other.

In Fig. 12, the casing is formed in two main parts so as to cover only the ends of the core. In this particular embodiment of the invention, the core m has a conductor m' passing straight through it from end to end and the two parts of the casing n n' are in-

sulated from each other so that the terminal wires of the secondary circuit may be connected to the casing rather than to the electrodes through the core, as indicated, and thus do away with the bosses. The core is provided with two circumferential flanges m^2 m^3 , and the ends or two parts of the casing are held in place by split nuts n^3 which are screwed into the inner ends of the two members of the casing, so as to hold said parts in place, as clearly illustrated. The terminal wires of the secondary circuit may be secured to the two parts of the casing by nuts o o' , as shown.

In all of these various embodiments of the invention, the exposed end of the plug may be equipped with a head or cap p screwed thereon, and having a transparent end p' through which the operator may observe the spark on the external end of the plug. In each of these embodiments of the invention, either end of the plug may be screwed into the cylinder so as to leave the other end exposed to view.

Having thus explained the nature of the invention, and described a way of constructing and using the same, although without attempting to set forth all of the forms in which it may be made, or all of the modes of its use, I declare that what I claim is:

1. A sparking plug for combustion engines having two pairs of complementary terminals or electrodes, each pair having an interposed spark gap, and provisions whereby either pair of terminals may be located within in a cylinder with the other pair visible.

2. A reversible sparking plug for combustion engines, having two portions adapted for alternate insertion into an engine cylinder, and having at each portion a pair of electrodes or terminals separated to form a spark gap, whereby sparks are formed within and outside of the cylinder.

3. A sparking plug for combustion engines, comprising an insulating core having at each of two distinct portions an electrode passing therethrough, said electrodes being insulated from each other by said core, and being adapted to be connected with a source of electricity, and a metallic casing inclosing said core and having electrodes complementary to said first-mentioned electrodes and separated therefrom to form spark gaps, said plug being constructed and arranged as described so that one pair of electrodes is visible outside the engine cylinder.

4. A sparking plug comprising an insulating core having lateral bosses or projections, electrodes extending through said bosses to the opposite ends of said core, a casing inclosing said core and having electrodes or terminals in complementary relation to said first-mentioned electrodes, and provisions whereby said first-mentioned electrodes may be connected to a source of electricity.

5. A sparking plug comprising an insulating core, having lateral bosses or projections, electrodes extending through said bosses to the opposite ends of said core, a casing inclosing said core and having electrodes or terminals in complementary relation to said first-mentioned electrodes, provisions whereby said first-mentioned electrodes may be connected to a source of electricity, and 10 means whereby each end of said plug may be attached to a cylinder so that the electrodes on said end will be in position to ignite the combustible material therein.
6. A sparking plug comprising an insulating core, electrodes extending through said core to the opposite ends of said core, a casing inclosing said core and having electrodes or terminals in complementary relation to said first-mentioned electrodes, said casing comprising a sleeve or bushing, and end portions 15 secured thereto.
7. A sparking plug comprising an insulating core, having lateral bosses or projections, electrodes extending through said bosses to the opposite ends of said core, and a casing inclosing said core and having electrodes or terminals in complementary relation to said first-mentioned electrodes, said casing comprising a two-part sleeve or bushing 20 apertured to receive said bosses or projections, and end portions secured thereto and holding the two parts of said sleeve together.
8. A double end plug for combustion engines, having a plurality of pairs of stationary electrodes one at each end, each forming 25
- a spark gap, means whereby said plug may be secured to an engine with either pair of electrodes in active igniting position in the cylinder, and the other pair out of the cylinder and a cap adapted to cover the exposed pair of electrodes. 40
9. A plug for combustion engines, having a plurality of pairs of electrodes, each forming a spark gap, means whereby said plug may be secured to an engine with either 45 pair of electrodes in active igniting position, and a cap adapted to cover the exposed pair of electrodes, said cap having a transparent portion.
10. A sparking plug comprising two distinct 50 portions each of which may be inserted in an engine cylinder, a pair of electrodes operatively located at each of said portions, and suitable electrical connections for supplying current to said electrodes. 55
11. A reversible sparking plug for combustion engines having a plurality of portions, each adapted for insertion into an engine cylinder with the others outside said cylinder, and having at each portion a pair of 60 electrodes or terminals to form a spark gap when the same is introduced into said cylinder.
- In testimony whereof I have affixed my signature, in presence of two witnesses.
